PASSING OF WARP THREADS THROUGH REEDS

Heinrich Meier, Uster, Switzerland, assignor to
 Zellweger A. G., Apparate- und Maschinen-
 fabriken Uster, Uster, Switzerland

Application April 13, 1945, Serial No. 588,152
 In Switzerland April 21, 1944

5 Claims. (Cl. 28—45)

1

This invention relates to the passing of warp threads through reeds.

For this purpose it is known to use devices by which the individual dents of a reed are intermittently divided off and warp threads that had been inserted in a hook of the reed selecting member of the pair of reeding members are passed through the reed by hand or foot operation of the device.

In effecting this hand or foot operation inadvertently, it may happen that the reeding members are operated prior to the thread or threads having been inserted in the hook, wherefrom faulty reedings ensue due to the fact that gaps are left through which no thread has been drawn. Such faulty reedings must be corrected by time consuming correcting operations. If such faulty reedings are not noticed at the proper time it may even happen that reeds which have already been drawn in must be subjected to repeated reeding all the way through.

Moreover, the passing of the reeding member by hand or foot operation is extremely fatiguing for the operator and this impairs efficiency. If the reeding member does not pass through the reed exactly at right angles to the plane of the reed dents a component force will arise which is directed at right angles to this plane, and the detrimental effect on the operation of the reed selector is such that this also causes faulty reedings. Furthermore, it frequently happens that reed dents of a relatively light construction are damaged, in consequence whereof, the drawn in threads are also damaged.

The said devices have the further drawback that the adjustment and adaptation of the reeding members to the various pitches, that is, the spaces between the reed dents, can be carried out only by trial and error which results in a waste of time and unreliable work. Under certain circumstances this adjustment is only possible by deforming one of the reeding members. A still further drawback consists in that the thread ends must in most cases be kept short and that the passing of the thread through the reed must be effected from below upwards, as a result of which in certain circumstances smooth threads, for example artificial silk threads, easily drop out of the gaps again.

The present invention is intended to eliminate the above mentioned drawbacks. It relates to a device for drawing warp threads through reeds, in which device the thread, after being set in the hook of one of the reeding members, actuates a feeler which in turn actuates the cou-

2

pling between the constantly running motor and the reeding mechanism in such a way that the latter is freed for one complete cycle and thereafter locked again in its initial position.

5 By this means the passage of the reed selector or upper reeding member is always exactly perpendicularly to the plane of the reed dents thus avoiding the setting up of a component force which would impair the functioning of the reed selector and thus the reliability of reed engaging as such. It is advantageous so to design the reeding device that the feeler only permits the reeding members to begin their movement when the thread or threads to be drawn in are securely held by the hook of the lower reeding member. The rhythm of inserting and passing the threads through the reed is, therefore, determined automatically and is thus no longer dependent upon the operator. This increases 10 the reliability and efficiency of operation and the economy of the reeding device.

For the purpose of adjusting and adapting the reeding members to reeds of various pitches it is advantageous to provide the device with a 15 rotatably adjustable drum whose circumference is graduated so that it can be set in correspondence with a fixed pointer.

The reeding device operates in such a manner that the warp threads are passed through 20 the reed from above downwards. A very practical thread end stripper is provided which permits of the said ends having a length of at least 8 inches, which makes it impossible for threads, including smooth threads, that have already been drawn in, to drop out again.

One embodiment of the present invention is 25 illustrated, by way of example, in the accompanying drawings in which

Fig. 1 shows a side elevation partly in section 30 with the members ready to receive a thread to be drawn in;

Fig. 2 shows a side elevation partly in section 35 with the members in position where the thread has just been drawn in;

Fig. 3 shows a cross section of the gear box 40 on the line III—III in Fig. 4;

Fig. 4 is a top view partly in section through 45 the gear box along the line IV—IV in Fig. 1, and

Figs. 5, 6 and 7 show details of the pair of 50 reeding members and of the adjustable drum.

Along two parallel tubes 1, the end portions of which are connected by means of end-pieces so as to form a supporting frame, the reeding device is displaceably guided by two flanged guide rollers 55 2 and a carrier roller 3. The flanged guide

rollers 2 are mounted on a bracket 4, one end of which carries a circular plate 5 which serves to deflect the threads and is secured to a gear box 6, which is composed of a lower and an upper part. On the said supporting frame a clamping rail 7 for the reed 8 is rotatably mounted at 7', in such manner, that the reed can be pivoted upwards by means of the clamping rail 7 into the vertical chain-dotted position as shown in Fig. 1.

The reed 8 is fastened in the clamping rail 7 by means of clamping screws 9 which are distributed at regular intervals along the whole width of the reed. The clamping rail 7 can be displaced in the direction of the reed dents, in accordance with the depth of the reed itself, by means of an auxiliary device which is not shown. Driving motion for the reading device is derived from an electric motor 11 which is flanged to the gear box 6, as shown in Fig. 4. One end of the motor shaft 15 carries a worm 13 firmly attached thereto and situated within the gear box 6.

The other end of the motor shaft is freely accessible so as to permit of actuating the reeding device by hand for purposes of adjustment when the motor is disconnected. The worm 13 drives a cross shaft 16, which is mounted in the gear box 6, through a worm wheel 14. To one end of the cross shaft 16 is fitted the hub 17 of a circular plate 18 for ejecting the threads 20 to be drawn in, on the circumference of which plate four strippers 19 are detachably fitted at regular intervals and project behind the deflecting plate 5.

The cross shaft 16 drives through a bevel wheel 22 and an appurtenant bevel wheel 23 having an equal number of teeth an auxiliary shaft 24 on which a ratchet wheel 21 is fixed and an eccentric 25 is loosely mounted, the hub of said eccentric being provided with a lateral lug 25'. The lateral lug 25' carries by means of a bolt 26 a pawl 28, which is urged by a spring 27 and for which a bolt 28' serves as a stop, in order to permit the pawl 28, when actuated on its operating arm to have just enough freedom to release the ratchet wheel 21, but not to allow the pawl 28 to partake of any outward movement beyond this.

With a view to preventing periodic displacements from arising when the strippers 19 remove the drawn threads 20, the number of strippers 19 corresponds to that of the teeth of the ratchet wheel 21.

The eccentric 25 engages with a fork one of the arms 29 of which (Fig. 3) is fixed to a shaft 31, which is journaled in the housing, and the other arm 30 is loosely arranged on this shaft 31. An extension 30' of the arm 30 of the said fork is drawn by means of a spring 29' against a stop pin 29'' on the arm 29, running bearing contact being provided between the cylindrical engaging surface of the eccentric 25 and the engaging surfaces of the fork arms 29 and 30.

The end of the reeding member carrier shaft 31 projects out of the gear box 6 and carries an arm 32 which is fixed to said shaft 31. An arm 32 by means of a screw bolt 37 (Fig. 5) a lever arm 38 supporting the reed selector 39 is mounted (Fig. 5). Further, on the reeding member carrier shaft 31 is axially displaceably arranged a holder 36 (Figs. 6 and 7) to which the lower reeding member 30 and a resilient blade 34 are secured by means of a screw 35 (Fig. 5). A stud 32'' which is fastened to the arm 32 and engages with a hole in the holder 36 transmits the pivoting movement of the arm 32 to the holder 36.

The lever 38, attached to arm 32 by means of bolt 37 is also held fast to arm 32 by means of the screw 41 fastened in lever 38 and in such fashion that the screw 41 engages in slot 32' of arm 32, and so that the two parts 32, 38 can be rigidly connected together by means of nut 40. When this nut 40 is loosened, the lever 38, together with the lower selector 39, can be snapped out into the dash-dotted line position shown in Fig. 5. This is necessary in order to make it possible to insert the reed 8 in the apparatus when operations are started. The reeding member carrier shaft 31 is provided with a threaded end-piece 53 (Fig. 6) on which a drum 52, which carries an internal screw thread and an external graduation, can be screwed by means of said thread into a position of adjustment corresponding with a pointer 36'. A compression spring 54 (Fig. 6) which abuts against the arm 32 and is pocketed in the hub of the axially displaceable holder 36 for bearing on said hub, tends to force the holder 36 axially against the end face of the drum 52.

By appropriately turning the drum 52 lateral spacing between the holder 36 and the arm 32 may be increased or decreased, thus altering the space between the lower reeding member 33, and reed selector 39 for the purpose of adapting this distance to reeds of different pitches.

On an axle 42 (Fig. 4) which is arranged on the gear box 6 a guide arm 43 is pivotally mounted to swing out of the full line position, as shown in Fig. 1, into the chain-dotted position indicated in this figure. The free end of the guide arm 43 carries a guide hood 44. This guide hood 44 is of U-shaped cross-section (channel section). If the thread, when it is being inserted in the apparatus, proceeding from the rear to the front (Fig. 1), is passed around the upper edge 44' of the guide hood 44, it slides over the two edges 44'' in the direction of the lower reeding member 33 which is disposed between the two side walls of this guide hood, and to such an extent that it slides of its own accord into the hooks 33' thereof. Numeral 45 designates a feeler 45 which is made of thin wire and which is guided in the guide arm 43 and is mounted by means of a bell crank lever 46 for pivoting movement about an axle 47 which is arranged on a supporting arm 48 which in turn is secured to an axle 49 rotatably mounted in the gear box 6. The free end of this feeler 45 is moved by the thread as soon as the latter enters the hook 33' of the lower reeding member 33. The other end of the feeler 45 is attached to a bell crank 46 pivotable about shaft 47 journaled in guide arm 48. The other end of the bell crank 46, when in the solid line position, bears on the arm 48 and is able to exert a pressure thereon inasmuch as the stop 46' bears on the arm 48. This occurs when the feeler 45 is contacted by the thread, so that the feeler is slightly moved in a counter-clockwise direction (Fig. 1). This movement of the feeler is transmitted through the bell crank 46 and stop 46' thereof to the arm 48 and hence causes shaft 49, to which one end of arm 48 is attached, to turn counter-clockwise. To the other end of shaft 49, which is journaled in the gear housing 6, is attached pawl 51 which is urged by spring 50 hooked to the gear housing 6. The force of said spring 50, acting through the pawl 51 serves to impart a clockwise rotary torque to shaft 49 (see Fig. 1). This torque ceases when the feeler 45 is loaded by insertion of a thread. This causes

shaft 49 to turn counter-clockwise and the movement is transmitted to the pawl 51.

The operation of the present reeding device is as follows:

The reed 8 to be prepared for weaving is inserted in the clamping rail 7 which is swung into the vertical position, that is, the position as shown in chain-dotted lines in Fig. 1 and is fastened thereto by the clamping screws 9. The guide arm 43 bearing the guide hood 44 is swung together with the feeler member 45 and the lever arm 38 carrying the upper reed reeding member, into the chain-dotted position as shown in Figs. 1 and 5. The drum 52 is adjusted commensurate with the pitch of the reed 8 to be prepared for weaving. Thereupon the reed 8 is swung together with the clamping rail 7 into the full line position in Fig. 1, in which position provision is made for the lower reeding member 33 to engage together with the switch 34 in the first gap of the reed to be provided with one or more threads. Lever arm 39, guide arm 43, bearing guide hood 44 and feeler 45 are then also pivoted back into the full line position as shown in Fig. 1.

When the electric motor 11 is started, it serves, through agency of worm 13, wormwheel 14, and cross-shaft 16, to cause the ejector plate 18, together with its four strippers 19, to rotate in the direction of the arrow in Fig. 4, so that the two bevel gears 22 and 23 will cause the auxiliary shaft 24 to rotate counter-clockwise (Fig. 1). This rotation is transmitted to the ratchet wheel 21 and the eccentric 25 with its lug 25' to which the pawl 28 is pivotally attached. The pawl 28, urged by spring 27, remains in engagement with the ratchet wheel 21; this position is shown in Fig. 2. Thus the entire mechanism rotates about the shaft 24. Hence the eccentric 25 effects an oscillatory movement of the bifurcated arms 29 and 30 which rest thereupon, so that an oscillatory movement of the reeding members 33 and 39 is produced. This oscillatory movement continues until the pawl 28 strikes pawl 51, as shown in Fig. 1, and this continues so long as the feeler is not depressed by a thread. If the pawl 28 strikes against the pawl 51, it will be lifted out of its engagement with ratchet wheel 21 and the loosely mounted eccentric, against the action of the spring 27, so that the eccentric 25 will be prevented from rotating further and will remain in its dead center position. The ratchet wheel 21 and also the stripper disk 18 will continue to be rotated by the motor which remains turned on.

Due to stopping of the eccentric 25 in its dead center position, the two reeding members 33 and 39 will remain in their furthest swung-out position as shown in Fig. 1, this is the position in which the device is ready for the reception of a thread.

When one or more warp threads are placed in the hook 33' of the lower reeding member 33, a slight pressure is exerted on the feeler 45 which is sufficient to rotate the feeler 45 together with the bell crank 46 to which it is attached in a counter-clockwise direction. The stop 46' of the bell crank 46 will thus bear against the carrier arm 48 and also serve to cause the latter to partake of a slight counter-clockwise rotational movement about the shaft 49. This rotation of shaft 49 is transmitted to the pawl 51 which is attached thereto, so that the latter will swing out of the position shown in Fig. 1 and assume the position shown in Fig. 2. Hence the pawl 51 releases pawl 28 so that the latter, under ac-

tion of spring 27 again snaps into engagement with the ratchet wheel 21. The continuously rotating ratchet wheel 21 thus carries along the pawl that is attached to the lug 25' of the eccentric 25 and hence causes the eccentric 25 to rotate. The rotation of eccentric 25 causes the forked arms 29 and 30 to swivel. As soon as the pressure of the thread on the feeler 45 ceases, the tension of spring 50 preponderates and serves to impart a clockwise motion to the pawl 51, the motion being transmitted to arm 48, bell crank 46 and to the feeler 45, so that the latter returns to its original position. Since the ratchet wheel 21 has the same number of teeth as the number of strippers 19 on the stripper disk 18, and since the two bevel gears 22 and 23 have the same number of teeth, it makes no difference into which tooth gap of the ratchet wheel 21 the pawl 28 may fall. The rotation of the eccentric 25 causes the fork arms 29 and 30 to swivel whereby the pair of reeding members or selectors 33, 39 execute an alternating motion. As a result of this, the hook 33' of the lower reeding member 33 passes through the reed downwards.

The movement of the reeding members 33 and 39 is initiated by the actuation of the feeler 45, which is itself actuated by the thread. The operator releases the thread, previously held in his hand, as soon as the reeding members 33, 39 start to move. By this means the thread or threads inserted in the hook 33' of the lower reeding member 33 are drawn through the reed and are thus brought within reach of one of the rotating strippers 19. The drawn in threads are then gripped by the relative stripper 19 and guided round the stationary deflecting plate 5 and the thread ends are drawn out of the hook 33' through the reed 8. The inserted thread ends are guided along the periphery of the deflecting plate 5 by the stripper 19, and after being released by the stripper 19, they assume, of their own accord, the natural position shown by the dash-dot lines in Fig. 1. The thread is designated by the numeral 20'.

Prior to the eccentric 25 and the pawl 28 having rotated through 360° the pawl 51 and the feeler 45 are snapped back to their initial positions by the urge of spring 50 so that the pawl 51 encroaches on the path of the pawl 28. By the said pawl then striking the pawl 51 the former is retracted from engagement with the ratchet wheel 21 so that the rotation of the eccentric 25 is stopped. While the eccentric 25 completes a full rotation the reeding members or selectors 33 and 39 and the resilient blade 34 execute an alternating movement, and thus bring the same into engagement with the following gap in the reed 8 in the manner already known in the art. Since the apparatus is arranged to be freely movable and displaceable on the support tubes 1, due to the rollers 2 and 3 it is able to follow the resilient pressure which the teeth of reed 8 exert on it through agency of reeding members or selectors 33, 39 and this produces the progression from tooth to tooth.

By the rotation of the drum 52, that is, its adjustment to the pitch of the reed, the distance between the reed selector 39 and the lower reeding member 33 is adapted to the pitch of the reed by means of the threaded end-piece 53. Faulty adjustment of the drum 52 would damage the reed dent lying in the path of the pair of reeding members 33, 39 and also the point of the reed selector 39. In order to avoid this eventuality the fork arm 30 loosely mounted on the auxiliary

shaft 24 is controlled by the spring 29'. If the resistance opposed to the reed selector 39 exceeds the admissible amount the fork arm 30, being loosely mounted on the auxiliary shaft 24, is swung as indicated in chain-dotted lines in Fig. 3, the tip of the reed selector 39 bearing against the reed dent. In such an event reeding is discontinued.

The present reeding device which can be built of any pitch of reed permits the perfect reeding of textile threads of any kind.

I claim:

1. In a device for passing warp thread material through a reed having a gap therein, a lower movable reeding member and an upper reeding member, a hook on said lower reeding member for inserting therein the warp thread material to be passed through the gap in said reed by mutual cooperation of said reeding members, a feeler for releasing, by virtue of said operation of inserting said thread material in said hook, said pair of reeding members for passing the said material through said gap, and a prime mover for imparting driving movement to said pair of reeding members.

2. In a device for passing warp thread material through a reed having a gap therein, a lower movable reeding member and an upper reeding member, a hook on said lower reeding member for inserting therein the warp thread material to be passed through the gap in said reed by mutual cooperation of said reeding members, a feeler for releasing, by virtue of said operation of inserting said thread material in said hook, said pair of reeding members for passing the said material through said gap, a common driving arrangement for said pair of reeding members, an eccentric included in said driving arrangement, a first pawl included in said driving arrangement for movement together with said eccentric, a second pawl included in said driving arrangement for cooperation with said first pawl by the latter pawl striking the former on the completion of each revolution by said eccentric, thereby to arrest said eccentric for intermittently setting said pair of reeding members at rest, and a prime mover for imparting driving movement to said driving arrangement.

3. In a device for passing warp thread material through a reed having a gap, a lower movable reeding member and an upper reeding member, a hook on said lower reeding member for inserting therein the warp thread material to be passed through the gap in said reed by mutual cooperation of said reeding members, a feeler for releasing by virtue of said operation of inserting said thread material in said hook, said pair of reeding members for passing the said material through said gap, rotatable stripping means for catching said thread material after its passage through said gap, a relatively stationary deflecting plate provided with a circular rim for cooperation with said stripping means for remov-

ing from the device said thread material after the latter was caught by said means and carrying it out of reach of said stripping means, a common driving arrangement for said pair of reeding members and said stripping means, and a prime mover for imparting driving movement to said driving arrangement.

4. In a device for passing warp thread material through a reed having a gap, a lower movable reeding member and an upper reeding member, a hook on said lower reeding member for inserting therein the warp thread material to be passed through the gap in said reed by mutual cooperation of said reeding members, a feeler for releasing by virtue of said operation of inserting said thread material in said hook, said pair of reeding members for passing the said material through said gap, means for spacing apart said reeding members in the direction of the length of the reed, a rotatable drum carrying a graduation for adjusting said spacing of said reeding members to the pitch of a given reed by appropriately rotating said drum as indicated by said graduation, and a prime mover for imparting driving movement to said pair of reeding members.

5. In a device for passing warp thread material through a reed having a gap, a lower movable reeding member and an upper reeding member, a hook on said lower reeding member for inserting therein the warp thread material to be passed through the gap in said reed by mutual cooperation of said reeding members, a feeler for releasing by virtue of said operation of inserting said thread material in said hook, said pair of reeding members for passing the said material through said gap, a spring-urged pivotal arm operatively connected with said upper reeding member, a means for automatically preventing said reeding members from cooperating with each other when said pivotal arm swings out against the action of said spring, due to said upper reeding member bearing against a reed dent adjacent to said gap, and a prime mover for imparting driving movement to said pair of reeding members.
